CLAIM

The ornamental design for a foldable lawn chair with canopy, as shown and described.

DESCRIPTION

FIG. 1 is a front perspective view of a foldable lawn chair with canopy, wherein the canopy is shown in an unfolded state;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a front perspective view of the foldable lawn chair with canopy, wherein the canopy is shown in a folded state. The broken lines shown in the drawings are for the purpose of illustrating portions of the article and form no part of the claimed design.
